CLAIM

The ornamental design for a multiple panel reflector dish antenna, as shown and described.

DESCRIPTION

FIG. 1 is a front isometric view of a multiple panel reflector dish antenna in accordance with the present invention.

FIG. 2 is a back isometric view thereof;

FIG. 3 is a front elevational view thereof;

FIG. 4 is a back elevational view thereof;

FIG. 5 is a left side view thereof, the right side being an identical image thereof;

FIG. 6 is a top plan view thereof;

FIG. 7 is a bottom plan view thereof; and,

FIG. 8 is an exploded perspective view thereof.

The broken lines shown in FIGS. 1-8 represent portions of the multiple panel reflector dish antenna that form no part of the claimed design.

1 Claim, 8 Drawing Sheets
